The ornamental design for a crash cart, as shown and described.

DESCRIPTION

FIG. 1 is a three quarter front, top, left side perspective view of a crash cart showing my new design;

FIG. 2 is a front elevational view thereof, taken in the direction of arrow 2 in FIG. 7;

FIG. 3 is a rear elevational view thereof, taken in the direction of arrow 3 in FIG. 7;

FIG. 4 is a top plan view thereof, taken in the direction of arrow 4 in FIG. 7;

FIG. 5 is a bottom plan view thereof, taken in the direction of arrow 5 in FIG. 7;

FIG. 6 is a left side elevational view thereof, taken in the direction of arrow 6 in FIG. 7, it being understood that the right side elevational view is a mirror image thereof; and, FIG. 7 is a view identical to FIG. 1 with descriptive legend directional arrows included which are necessary for better understanding of the drawing in accordance with 37 CFR 1084(o) and appropriate with good engineering practices, so as to best indicate in what directions previous views are taken so that nothing regarding the design sought to be patented is ambiguous or left to conjecture.

In the drawings, the broken lines depict unclaimed subject matter only an form no part of the claimed design.
